CLAIM

An ornamental design for a scored carton, as shown and described.

DESCRIPTION

FIG. 1 is a front perspective view of the scored carton of the present invention.

FIG. 2. is a back perspective view of the scored carton of the present invention.

FIG. 3. is a side view of the scored carton of the present invention.

FIG. 4. is a side view of the scored carton of the present invention.

FIG. 5. is a cutaway view taken along line 5—5 of FIG. 4 of the scored carton of the present invention; and,

FIG. 6. is a cutaway view taken along line 6—6 of FIG. 4 of the scored carton of the present invention.

The broken lines showing of portions of the container are for illustrative purposes only and forms no part of the claimed design.
